UNITED STATES PATENT OFFICE.

GEORG NÖLLMANN, OF BUENOS AIRES, ARGENTINA.

ROTARY MOTOR.

1,388,438.

Specification of Letters Patent. Patented Aug. 23, 1921.

Application filed May 18, 1920. Serial No. 382,374.

To all whom it may concern:

Be it known that I, GEORG NÖLLMANN, a citizen of the German Republic, residing at Calle Maipú 671, Buenos Aires, Argentine Republic, have invented new and useful Improvements in a Rotary Motor, of which the following is a specification.

This invention has for its object an improved rotary motor, a main feature of which is the simplicity of its construction, substantially consisting of a fly wheel of suitable dimensions, according to the speed and degree of power to be developed, whose periphery is combined with one or more propelling chambers and is provided with a series of projecting paddles, adapted to move radially under the action of a cam.

The novel motor according to this invention may be operated by steam, explosion gases, water, compressed air, etc., being also adapted to operate as an air compressor or as a simple lifting and forcing pump.

Owing to the limited space occupied by the structure, as well as to its simple construction and large yield of motive power developed thereby, this motor offers considerable advantages over the constructions actually known.

The direction of running may be reversed, by simply reversing the direction of circulation of the operating fluid.

For the better understanding of this description, illustrative detailed drawings have been annexed thereto, wherein:—

Figure 1 is a view in front elevation of a rotary motor or engine constructed in accordance with my invention.

Fig. 2 is a view of the same motor, partially in section and showing three propelling chambers.

Fig. 3 is a sectional elevation on the line A—B of Fig. 1.

In said drawings, 1 is the motor wheel, mounted on the shaft 2, supported in turn on suitable brackets 3 which may be of any convenient shape and dimensions. To said motor wheel is secured a series of paddles 4, adapted to operate in recesses or cavities formed within the wheel, each of the paddles being fixed to a stem 5 which tends to move toward the center of the wheel under the action of a spring 6 and carrying on its end a roller 7, mounted to move in engagement with a cam 8, as to cause by this means the radial movement of said paddles or plates.

In combination with the motor wheel 1 are provided one or more propelling chambers 9, suitably retained in position, into which open the pipes 10 and 11, adapted to be used alternately for the admission or exhaust of the operating fluid, according to the direction of running of the motor.

Each of the chambers or compartments fits well with its end in the periphery of the fly wheel and with its sides to the rims of the same, being maintained in this position by means of the radial arms 12, the length of which may be adjusted by means of nuts 13. Between the motor wheel and the chambers is left a space extending through a smaller or larger sector, according to the number of paddles used on the motor wheel.

It will be readily understood that the direction of running of the wheel will depend on the direction given to the operating fluid.

Referring to Fig. 2, it will clearly be seen that when the fluid enters in the direction indicated by the arrows, the paddle 4 which closes the space between the chamber 9 and the wheel 1, will be propelled so as to cause the wheel to rotate until the next following paddle is caught by the fluid and operated in substitution of the foregoing one, thereby producing the continuous rotary motion of the wheel.

Said paddles, on being submitted to the propelling force of the steam, air, etc., when entering into the chamber or compartment, will be lifted by the action of the cam 8 and will descend at the instant in which its operation is replaced by that of the following paddle, so as to allow of the exhaust to take place without interfering with its passage at the point of fitting between the chamber and the wheel.

It will be apparent that, two or more of the above described motor wheels may be coupled to the same shaft and that the number of propelling chambers may be increased according to the diameter and number of paddles of each of said wheels.

I now declare that what I claim as new and desire to secure by Letters Patent, is:—

A rotary motor comprising a fly wheel having spokes, flanges on each side of the wheel rim forming an annular chamber, said rim projecting laterally at one side of the spokes and having pockets formed therein, blades in said pockets, stems on the blades projecting from said pockets centrally of the

channel and at one side of the spokes, springs on the stems normally retracting the blades, a stationary cam at the center of the wheel over which the ends of the stems travel, a 5 detachable steam channel extending over a portion of the rim and having sides fitting over the flanges of the rim, a stationary hub,

and radially adjustable rods connecting the channel to the hub.

GEORG NÖLLMANN.
